TUNING DEVICE FOR RADIO RECEIVERS

Frank Allen Mitchell, London, England, assignor
to Electrical & Musical Industries Limited,
Middlesex, England, a company of Great Britain

Application September 1, 1938, Serial No. 227,881
In Great Britain September 1, 1937

5 Claims. (CL 172—239)

This invention relates to tuning devices for radio receivers of the kind in which the tuning device can be rotated to one or other of a plurality of predetermined positions by the operator either at the receiving apparatus or from a remote point.

Proposals have heretofore been made whereby a radio receiving apparatus may be tuned mechanically under the control of the operator as, for example, by depressing one of a plurality of push buttons which causes rotation of a tuning condenser by energising an electric motor, the tuning condenser being rotated by a predetermined amount after which it is brought to rest in the desired station receiving position.

Other proposals have also been made but most of these are not satisfactory owing to the complication of the mechanism employed resulting in large manufacturing costs, service difficulties and uncertainty in operation.

It is the chief object of the present invention to provide an improved tuning control for automatically rotating a tuning device, for example, a tuning condenser, into a plurality of station-receiving positions under the control of the operator either at the receiver or from a remote point.

According to the invention the tuning control comprises a selector member having conducting and insulating zones thereon and a plurality of electrical contact members in engagement with said selector member so as to be capable of contacting with the insulating or conducting zones thereon, some of said contact members serving to control directly or to operate relays to control an electric motor for rotating said selector member and a tuning device connected thereto to predetermined positions, the arrangement being such that when a selected contact member is in engagement with an insulating zone of the selector member the electric motor is rotated in one direction and when a selected contact member is in engagement with a conducting zone the electric motor is caused to rotate in the reverse direction.

In the preferred form of the invention the selector member comprises a disc directly coupled to the shaft of the tuning device which, in most cases will be a variable condenser, the disc generally being of conducting material but having an insulating zone thereon, said insulating zone being so formed that during rotation of said disc the contact members bear either on the conducting or the insulating zones of said disc. The disc is arranged to be angularly moved

5 through 180° with the tuning condenser and the junction between the insulating and the conducting zones of said disc is preferably of serrated form and during angular movement of said disc an edge of each serration moves past a corresponding one of said contact members. The tuning control may be operated by a selector mechanism of the type disclosed in United States Patent No. 2,100,609 or by a sliding contactor, but in the case of the present example is preferably operated as a result of depression of one of a plurality of push buttons, each push button being associated with one of said plurality of said contact members so that on depressing a push button the tuning condenser is rotated for a predetermined extent determined by the relative positions of the contact member associated with the depressed push button and the edge forming the junction between the conducting and insulating zones associated with the particular contact member. If, on depressing one of said push buttons, the associated contact member is in engagement with the insulating zone of said disc, then the tuning condenser would be rotated in one direction, but if the selected contact member is in engagement with the conducting zone of said disc, then the tuning condenser will be rotated in the opposite direction.

15 In order that the present invention may be clearly understood and readily carried into effect it will now be described with reference to the accompanying drawings in which:

Figure 1 is a circuit diagram of a tuning control in accordance with the invention.

Figure 2 is an enlarged view of the selector member.

Figure 3 is a plan view of a selector box having a plurality of push buttons for use in the invention.

Figure 4 is a plan view of the underside of the box shown in Figure 3 with the bottom of the box removed.

Figure 5 is a cross-section view taken along the line 5—5 of Figure 4 with the bottom of the box in position.

Figure 6 and Figure 7 are respectively side elevation and plan views of a modification showing another selector member which may be employed in accordance with the invention.

Figures 8 and 9 show different methods of supporting and adjusting the contacts on the selector member.

Figure 10 illustrates an alternative form of selector box having a slideable selector, and

Figure 11 is a circuit diagram of another modi-

lication having a simplified form of selector member using circumferential adjustment for the contact members which may be employed in accordance with the invention.

Referring now to Figure 1 of the drawings, the mechanism in accordance with the invention comprises a selector member 6 which, as shown in detail in Figure 2, comprises a disc of metal 7, the metal constituting the aforesaid conducting zone whilst the zone of insulating material 8 is recessed into the surface of the disc or arranged in an aperture stamped out from the disc. As aforesaid, the disc is rotated with the tuning condenser, not shown, and arranged for rotation through an angle of 180° by a reversible electric motor hereinafter referred to. Arranged diametrically of the disc 7 is a plurality of contact members A-O, as shown in Figure 1, the contact members being mounted in a block 9 of insulating material the ends of the contact members having contact elements which bear on the surface of the selector disc 7. Since the disc rotates only through 180°, eight of the contact members are arranged on the right-hand side of the disc and the other seven contact members are arranged on the left-hand side, as shown in Figure 1, the disc 7 having insulating zones arranged in the manner hereinafter referred to. The contacts A, B, C, D, E, F, G, and the contacts H, I, J, K, L, M, N on either side of the disc serve as station selector contacts, the function of the remaining contact O being hereinafter referred to. The junction between the conductor and insulating zones of the disc is, as shown in Figure 2, of serrated form providing edges 10. An edge 10 is provided for each contact and each edge is spaced radially from the centre of the disc a distance such that it is adapted to move in a path which will bring it into engagement with its associated contact member. Referring to Figure 2, the selector member is shown in its extreme position of movement in an anti-clockwise direction and the edges 10 at the upper half of the member 6 are adapted to move into engagement with their respective contact members A . . . G when the selector member is moved in a clockwise direction. Similarly the edges 10 at the lower half of the member 6 are adapted to move into engagement with contacts H . . . N when the selector member is rotated in a clockwise direction.

The edges 10 of the insulating zone are spaced angularly round the selector member so that the selector member, and therefore the tuning member to which it is mechanically coupled, will occupy a different angular position as each edge of the insulating zone comes into engagement with its associated contacting member.

The arrangement of the apparatus is such that the selector member and tuning element of the radio receiver are brought to rest when an edge 10 of the insulating zone of the selector member lies substantially in engagement with the selected contact member, and the radio receiver is "tuned in" to receive a selected station when the tuning element is in that position, as will be described more fully hereinafter. Each of the contact members A-O is connected by the leads shown to a corresponding number of sockets mounted on a plug panel indicated by the dotted line 11, the plug sockets being lettered with the same lettering as the contact members. To select a particular station, in the example shown in Figures 1 to 5, one of a plurality of five push buttons 12 is depressed, the push buttons being associated

with selector and switch controls mounted in a selector box shown in detail in Figures 3, 4 and 5. For the sake of convenience in Figure 1 only one push button 12 and associated selector switch contacts are shown and five sockets A, D, H, I and M are connected by a single lead to one of the switch contacts although it will be understood that each of the said sockets will, in practice, be connected by a separate lead to the appropriate switch contact of the respective one of the five push buttons shown in Figure 3. If desired, the selector box 62 may contain fourteen push buttons for association with the fourteen contact members A-G and H-N, but in the arrangement illustrated in Figures 3, 4 and 5 where only five push buttons are employed, a removable multi-pin plug may be provided whereby the push buttons may be connected to any group of five contact members according to the requirements of the operator. The selector box or panel may be mounted on the cabinet of the radio receiver or in a position remote therefrom and connected to the plug panel by a flexible or other lead terminating in the removable plug, or, if desired, several selector boxes or panels may be connected to the same radio receiver.

Each selector switch comprises a push button 12 projecting through an aperture in the selector box and a bank of switch contact fingers 13, 14, 15, 16 is located beneath the push button. The uppermost contact finger 16 is insulated from the push button by a strip 17 of insulating material and is adapted to engage with contact finger 15 to close a circuit when push button 12 is depressed. Contact finger 15 is insulated from contact 16 by the strip 18 of insulating material and, when depressed by movement of the push button, contact finger 15 causes contact finger 14 to engage contact finger 13 to close a second circuit. The lowermost contact 13 lies adjacent the metal base plate of the selector box, which plate is connected to earth in any suitable manner. A plate of insulating material 19 is mounted on the metal base plate so that the contact finger 13 is insulated from the base plate along a portion of its length, but the arrangement is such that the end of contact finger 13 under the push button 12 is adapted to come into contact with the base plate when the push button is depressed to close a third circuit. When a push button is depressed all of the contact fingers 13, 14, 15 and 16 are depressed and when the push button is released it is held in an intermediate position by a latch 20, which is common to all of the push buttons, as shown in Figures 4 and 5, the latch being operated by a relay 21 and released as hereinafter referred to. The latch 20 comprises a bar pivoted on trunnions 22 and the end of each push button is provided with a shoulder 23 with which the latch engages when the relay is energised to draw the latch towards the push button.

Direct current for the operation of the relay 21, and further relays hereinafter described, is derived from a contact rectifier 24 connected to a secondary winding 25 of a mains transformer indicated generally at 26. The selector member 6 and the tuning condenser are rotated by a reversible electric motor which, as shown, may be an induction disc motor and is supplied with current by tapping the primary winding 27 of the transformer, as shown. The electric motor has a main current winding 28 and two voltage windings 29 and 30 which control the direction of rotation of the motor, only one of said voltage windings being in circuit at a time. Current is

supplied to the motor on depressing one or other of the push buttons 12 through the medium of a relay 31. The relay 31 is associated with contact fingers 33, 34, 35, 36, 37, 38, and 39, which are normally maintained apart, as shown in Figure 1, but which, when the relay 31 is energised, as hereinafter described, are closed, the contact finger 33 engaging contact finger 34, contact fingers 35, 36 and 37 engaging one another, and contacts 38 and 39 likewise engaging one another. A further relay 32, is provided, associated with contact fingers 40, 41, 42, 43, 44, 45 46, 47 and 48, which are normally maintained in the positions shown in Figure 1, but which, when the relay is energised, as hereinafter referred to, are closed in the following manner. The contact 40 is moved out of engagement with contact 41 and the contact 42 moved into engagement with 41. Contact 43 is moved out of engagement with contact 44 and contact 45 moved into engagement with contact 44. Contacts 46 and 47 are engaged and thereafter contact 48 moved out of engagement with contact 47. Relay 31 controls the supply of current to the current coil 28 of the motor and also to the changeover switch represented by contact fingers 40, 41, 42 which permits current to flow through one or other of the potential coils 29, 30 of the motor.

Relay 32 controls the direction of rotation of the motor and when energised opens the circuit of potential coil 30 which energises the motor to rotate the selector disc in a clockwise direction and closes the circuit of potential coil 29 to reverse the direction of rotation of the motor and cause movement of the selector disc in an anti-clockwise direction. The various switch contacts associated with the relays 31 and 32 are connected to the motor, to the contacts associated with the selector member and to the contacts of the selector box, as shown, the contacts 37 and 45 being connected to earth. The mains transformer 26 may be the same transformer that supplies current for the operation of the radio receiving apparatus and, as shown, further secondary windings are provided for heating the valves and supplying operating potentials, the secondary winding 49 supplying current to the cathodes of the valves through normally closed contacts 50 and a further secondary winding 51 supplying current for the rectifier valve of the receiving apparatus through normally closed contacts 52, whilst a pilot lamp 53 normally derives current from the primary 27 of the transformer through normally closed contacts 54. The function of the contacts 50, 52 and 54 will be hereinafter referred to.

The operation of the mechanism is as follows. Assuming that it is desired to select a station represented by the contact M, and that the selector disc is, as shown in Figure 1, in its extreme position of anti-clockwise rotation so that contact M bears against the insulating zone of the disc, then the appropriate push button 12 is depressed which closes the contacts 13 and 14 and causes contact 13 to bear against the earthed plate of the selector box. Earthing of contact 13 closes a circuit which includes the transformer secondary 26, rectifier 24, relay 31, conducting lead R, switch contact 13, earth plate of the selector box and so to earth and back to the transformer winding 25. Relay 31 is thus energised and closes switch contacts 33-34. Closure of switch contacts 33-34 completes the driving motor circuit and current flows from transformer primary 27, switch contacts 33, 34, 75

current coil of motor, and back to the transformer primary 27. Current also flows from switch contacts 33, 34 to the closed switch contacts 40, 41 controlled by relay 32, potential coil 30, and back to transformer primary. The driving motor is thus energised, and since potential coil 30 is energised the selector disc and the tuning element of the radio receiver will commence to rotate in clockwise direction, and the edge 10 of the insulating zone of the selector disc will move towards contact M.

Referring again to the selector switch, pressure upon push button 12 has also brought switch contact 14 into engagement with contact member 13. A further circuit is thus closed which includes transformer secondary 25, rectifier 24, lead U, relay 21 in the selector box, contact members 14 and 13, earthed plate of the selector box and transformer secondary 25. Relay 21 is then energised, and the latch 20 is drawn into position to latch push button 12.

It will be understood that the energisation of relays 31 and 21, the closure of the various contacts controlled by relay 31 and movement of latch 20 of relay 21 is effected instantaneously, and after a momentary pressure has been applied to press button 12, pressure upon the press button may be removed so that the bias of the switch contact blades will return it to an intermediate position in which it is latched by the latch 20. When the push button 12 returns to its intermediate position selector switch contacts 13, 14 remain in engagement, but contact is broken between switch contact 13 and the earthed plate. The motor controlling relay 31 and the selector box latching relay 21 continue to be energised, however, through the following circuits: terminal R of relay 31, resistance 13a, closed switch contacts 46, 47 of relay 32, switch contacts 35, 36 and earthed contact 37 of relay 31, which are closed since relay 31 is energised. Current also flows from contact S on relay 21 through selector switch contacts 14, 13 and resistance 13a.

Referring again to the act of pressing the selector switch push button 12, this action also causes contacts 15, 16 to close, and the said contacts are connected in a circuit which includes the earthed selector disc, contact member M, 50 socket member M on plug panel 11, selector box switch contacts 15, 16, lead Q, switch contacts 46, 48 of relay 32 which are at present open, since relay 32 is not energised.

As stated hereinbefore, the selector disc is 55 rotating in a clockwise direction and the edge 10 of the insulating zone is moving towards contact element M. As soon as rotation of the selector disc is sufficient to cause the contact element M to pass from engagement with the insulating zone to engagement with the conducting zone of the disc, relay 32 is energised through transformer secondary 25, rectifier 24, relay 32, lead Q, closed contacts 38 and 39, selector switch contacts 16, 15, socket M on plug panel 11, contact member M, selector disc, earth and so back to transformer secondary 25.

Energisation of relay 32 causes changeover switch contacts 40, 41, 42 to be reversed thus de- 70 energising voltage coil 30 of the electric motor and energising voltage coil 29 of the motor. The direction of rotation of the motor and thus of the selector disc 6 and the tuning element is reversed and the selector disc is rotated in an anti-clockwise direction to bring the insulating zone

of the selector disc into engagement with the contact element M.

Energisation of relay 32 also causes contact member 48 to engage with contact member 46 to provide alternative path for current flowing through relays 31, 21 and resistance 13* and immediately after contacts 48 and 46 engage contact 46 is disengaged from contact 47. The effect of this is to transfer control of relays 31 and 21 from switch contacts 35, 36, 37 of relay 31 to the selector disc and current now flows from relays 31 and 21, through resistance 13*, switch contacts 46 and 48 of relay 32, lead Q, switch contacts 16, 15, of selector switch, contact socket M of plug panel 11, contact member M, the conducting zone of the selector disc and so to earth. The motor continues to rotate the selector member in an anti-clockwise direction, after relay 32 has been energised, until the contact M bears against the insulating zone of the selector member and when this position is reached the circuit for the motor is disconnected through the opening of the contacts 33 and 34 on relay 31. The de-energisation of relay 21 which occurs at the same time as de-energisation of relay 31 owing to the circuit being broken by contact member M bearing against an insulating zone, causes the push button of the selector switch to be unlatched and thus allows switch contacts 13, 14, 15 and 16 to be opened, and the press button 12 to be returned to its off position due to the return movement of uppermost contact finger 16. Relay 32 is thus de-energised since the contacts 15, 16 have opened. In this position the tuning condenser has been rotated to a position to tune in a station represented by contact M, the selector member 6 having been rotated until, as above mentioned, the contact M is in engagement with the insulating zone of the selector disc. The receiving apparatus is thus tuned to the required station and the relays and the motor are de-energised and the various contacts are returned to the positions shown in the drawing.

When the desired station has been tuned in and the relays have thus been de-energised, it will be possible to operate the tuning mechanism from another selector box 62 located in another position but connected to the plug panel 11 by parallel circuits.

In some cases the position of the selector disc 6 may be such that the selected contact member is bearing upon a conducting zone of the selector disc. In such cases relays 21, 31, and 32 will all be energised substantially simultaneously when the press button is depressed and the various contacts operated by the press button, and relays 31 and 32 will be opened or closed in the manner hereinafter described, so that the motor rotates the selector disc in an anti-clockwise direction until the selected contact member engages with the insulating zone of the disc to de-energise relay 21 and 31 and to cause the circuit of relay 32 to be de-energised.

It will be appreciated from the above that when the stationary contact of a selected station bears against an insulating zone of the selector member, relay 31 will be energised so that the motor rotates the selector member 6 in a clockwise direction. Conversely, when the contact member of a selected station bears against a conducting zone of the selector member 6, the selector member will be rotated in an anti-clockwise direction.

It will also be appreciated from the above that although the selector disc may move in either di-

rection to bring the edge of the insulating zone into engagement with the selected contact member, the final movement of the selector disc towards its stopping position always occurs in one direction only, that is to say, in the present instance in an anti-clockwise direction. This is a desirable feature which permits the tuning adjustments of the apparatus to be made with great accuracy.

10 A radio receiver to which the invention may be applied will, in most cases, be provided with the usual manual control and if, for example, during such manual control, the selector member 6 is rotated in a clockwise direction from the position shown in Figure 1 through 180°, it will be seen that the right-hand contacts on the selector member are traversed first by the insulating zone and then by the conducting zone and one or more contact members may engage the insulating zone again in this extreme position. If one of the contact members bearing against the edge of the insulating zone were selected, the result would be that only the relay 31 would be energised and the selector member would be rotated in a clockwise direction, whereas the apparatus requires that under these conditions the selector member should rotate in an anti-clockwise direction. To obtain this reversal of rotations to an anti-clockwise direction in the extreme position, it is necessary to arrange for the relay 32 to be energised when a push button is depressed. This is effected by so shaping the conducting zone of the selector member 6 as indicated at 56 so that when the selector member is in the position above-mentioned the contact G bears against the conducting zone 56. The contact G, as will be observed from Figure 1, is connected to the contact 38 of relay 31 and when the relay 31 is energised the contact 38 is moved into engagement with contact 36 with the result that current then flows through relay 32, the contacts associated with the relay 32 are operated as above described and the direction of rotation of the motor is reversed so that the right-hand contacts and the selector member are brought into contact with the conducting zone, the contact G then engaging the insulating zone. Thereafter the contacts associated with the selector box become effective to control the rotation of the selector member 6, as above described.

55 To enable the receiving apparatus to be switched out of operation from the selector box, a further button 12A is provided as shown in Figure 3, this button being connected to the contact O on the selector member 6 so that when the button 12A is depressed the selector member 6 is rotated in an anti-clockwise direction until the extreme position is reached. It will be observed from Figure 1 that the contact O is normally in engagement with the conducting zone 7, but in the extreme position it comes into engagement with the insulating zone, which is specially shaped for this purpose, as indicated at 57. The selector member is therefore brought to rest in this position. The contacts 50, 52 and 54 are mounted adjacent the selector member 6 and a striker 58 is provided on the selector member so that in the extreme position of said member the striker engages the contacts to open the circuits controlled thereby so that the current to the receiving apparatus is switched off.

56 The contacts 36 and 37 associated with relay 31 and contacts 44 and 45 associated with relay 32 are provided in order that on energisation of either relay 31 or 32 the loudspeaker of the re-

ceiving apparatus is muted to permit of silent tuning.

The selector box is preferably provided with a pair of plug sockets to enable a loudspeaker to be plugged into the selector box in cases where it is located, for example, in a different room to that of the receiving apparatus.

One such arrangement suitable for a moving coil loudspeaker with a permanent magnet is illustrated in Figures 1 and 4 of the drawings.

The secondary winding 58 (Figure 1) of the output transformer of the radio receiver, the primary winding of which is not shown, is earthed at one end and the other end is connected to switch contact 44 of relay 32. A lead from contact 43 is connected to one of two plug sockets 59 and the other plug socket is connected to the adjustable arm 60 of a potentiometer the resistance element 58 of which is connected at one end as illustrated in Figure 1 to the lead from contact 43 and at the other end to contact O of plug panel 11 and so to earth.

The plug sockets 59 are adapted to receive the speech coil leads of a loudspeaker, not shown, and the strength of the reproduced sounds may be controlled by adjustment of the arm 60 of the potentiometer which is provided with a suitable control member projecting through the selector box and terminating in a control knob 61.

It will be appreciated that the distance between adjacent edges 18 of the selector member 8 corresponds to a range of adjustment of the tuning condenser and, consequently, by adjusting the vertical heights of the station selector contacts bearing against the selector member 8, it is possible for the operator to select what stations he may require to be selected on operation of the push buttons. To enable the operator to adjust the station selector contacts, it is preferred to mount the station selector contacts in such manner in the insulating block 8 that their vertical positions can be adjusted. For this purpose the station selector contacts may be held in grooves or slots in the block 8 and screws may be provided in engagement with the contacts so that on rotating the screws the vertical positions of the station selector contacts can be adjusted.

It will be understood that if desired a number of selector discs and associated contact members may be employed and, furthermore, instead of employing selector discs, drums or cylinders may be used.

Reference is now made to Figures 6 to 9 of the accompanying drawings which show a modified form of selector member and contacts that may be employed in accordance with the invention.

In Figures 6 and 7 the tuning device of the receiver is shown as a condenser 101 and the cabinet front of the receiver is shown by the chain line 102.

The station locating mechanism is preferably supported entirely on the condenser mounting plate 110 to keep strict relation between the parts and to minimise vibration.

The station selector member in the form of a disc 103 is rigidly mounted on the condenser shaft 105 which also carries the usual station indicating pointer 106. The selecting member 103 is engaged by the friction drive 107 which is adapted to be rotated in known manner by means of the hand operated knobs 8, or by an electric motor (not shown) such as the motor described in connection with Figures 1 to 4 of the accompanying drawings which is coupled to the control shaft 9.

The mounting plate 110 also carries a plurality of contact members 111 to 119 in spring engagement with the selector member 8, the contacts 111 to 119 being mounted in grooves cut in a block 120 of insulating material rigidly attached to the plate 110. The plate 110 also rigidly supports the frame 121, which carries adjusting means whereby the contacts 111 to 119 may be adjusted to predetermined positions.

The contact members 111 to 119 are each preferably in the form of a flat strip of springy metal having a contact point 122 at one end and bent to a V shape at the opposite end, as shown in Figures 8 and 9, so that pressure on the short limb will keep the contact strip 111 located in its groove in the block 120. The extreme end of the short limb is bent at right angles and engages the recessed end 123 of an adjusting lever 124 pivoted at 125. The lever 124 has a toothed segment 126 formed thereon which is engaged by a screwed adjusting member 127 mounted on the frame 121 carried by the mounting plate 110 as hereinbefore mentioned. Each lever 124 is spaced from adjacent levers by a spring pressed non-rotatable spacer 128 whereby they are adjustable independently. The screw 127 is mounted so that it has no end play, but can be rotated by the knurled head 128 or by the slotted head 129 to rotate the lever 124 and thereby move the contact strip 111 and contact 122 angularly relative to the station selector disc 103. Similar adjustment means may be provided for the contact strips 111 to 119.

Each of station selecting contacts 111 to 119 is adapted to operate in conjunction with one of the stepped edges of an insulated zone 104 as described in connection with Figures 1 to 5.

The zone of insulation 104 formed on the selector disc 103 is formed with a plurality of radially spaced steps, as shown in Figure 7, so arranged that the adjustable contacts 111 to 119 may be supported in parallel relation and with their contact points lying approximately along a line radial to the disc 103. The adjusting levers 124 may thus be mounted on a common shaft 125 supported by the frame 121 and the screwed adjusting members 127 may be arranged in one or more lines parallel to the shaft 125. The ends of the adjusting members 127 preferably pass through apertures in a panel 133 mounted on the frame 121 and the panel is located in an aperture in a wall of the cabinet whereby adjustments may be made from the exterior of the cabinet. The panel may be provided with waveband or other markings to indicate the frequency range of each adjustable contact of the rotary switch.

Figure 8 shows a modified form of adjustment device 124 for the adjustable contacts 111 to 119. The lever 124 is formed with a projection 124a which is located in a recess in the contact 111, and the edge 126 of the lever is provided with teeth which mesh with a worm 121. The worm shaft carries a knurled disc 128 which projects through an aperture in a wall of the cabinet and is adapted to be rotated to adjust the contact 111.

Figure 9 shows a further modification of the adjustment device 124 wherein the lever itself projects through an aperture in the cabinet and may be rotated to adjust the contact 111.

Referring now to the modifications shown in Figures 10 and 11 of the accompanying drawings the station selector mechanism shown in Figure 10 comprises a sliding contact member 201 where-

by a chosen station name is selected, and a single press-button 203 adapted to put the contact member 201 into operative circuit with the relays so that they function in the same manner as described with reference to Figure 1. In selector panel unit Figure 10, 203 may be connected to the plug panel 11 in place of or in parallel with the press button box 62 in Figure 1, and the remainder of the circuit beyond the panel 11 may remain as in Figure 1.

When a desired station is to be selected, the sliding contact 201 is moved to the desired stud 204 (c for example) to connect the adjustable contact member C operating on the disc 6 (Figure 1) to the spring contact finger 205 (Figure 10). The actuating button 203 is then pressed to close contact fingers 205, 13 and 14 and contact fingers 15 and 16. This permits current to flow from the rectifier 24 (Figure 1) through magnet 206, contact fingers 14, 205 to earth through connector P as described with reference to Figure 1, to cause magnet 206 to hold the contacts 15 and 16 as well as 13 and 14 closed so that current is then able to flow from the rectifier 24 through relay 31 (Figure 1) and the holding magnet 206 returning to earth through connection R and resistance 13A as described with reference to Figure 1. The press-button is returned as soon as the operator's finger is removed, by the spring contact 205, the magnet 206 keeping the circuit active until the desired station is found. In the modification illustrated in Figure 10 the electrical components of the complete mechanism operates exactly as described with reference to the circuit of Figure 1. The magnet 206 becomes demagnetised when the desired station is found and the selector panel contact fingers 13, 14, 15 and 16 return to their neutral position to break the circuit through the slider 201 so that any other station may be selected on it or on another panel or press-button selector working in parallel therewith.

The above selector mechanism shown in Figure 10 or the press-button panel (Figures 1, 3, 4 and 5) can be built into a portable loud-speaker case, the connections 59 (Figure 1) being permanently connected to the loud-speaker. The case or the panel may sometimes carry an additional switch or press-buttons to operate a wave-change device, such as a relay, on the wireless receiver, for example in the manner referred to in U. S. Patent No. 2,100,609 previously referred to.

Another modification of the invention is shown diagrammatically in Figure 11 in which the disc 207 of insulating material has a metal segment 208 inserted therein so that the surface of 207 and 208 are flush. The disc 207 is rigidly attached at 209 to the rotatable tuning element of a wireless receiver and the whole is adapted to be driven by the reversible electric motor 210. A plate preferably of insulating material 211 is non-rotatably mounted in front of the rotatable disc 207 and carries a number of slidable contact members 212 capable of adjustment into desired station selecting positions in the following manner. The tuning element (not shown) is first turned by hand until the desired station is in tune, then one of the contact members 212 is released by means of the screw 213 and is slid around the slot 214 until the contact edge 215 lies on the insulated portion close to the edge 216 of the metal segment 208. The screw 213 is then tightened and the name or cypher for the station inserted in the control box or panel 217 against the press-button, switch or stud by which the

station is to be automatically found. All the sliding contact members 212 are adjusted in this way for the various stations which are to be tuned automatically.

If desired the remainder of the mechanism may be as described with reference to Figure 1 or 10, without alteration, but if it is desired to omit the use of relays the circuit may be arranged as shown in Figure 11, in which the control panel 217 has a series of press-buttons 230, each operating a contact finger 218 connected by a separate lead 219 to its associated contact member 212. The A. C. supply indicated conventionally in Figure 11, from the mains or a transformer (at 25 volts for example) is connected to the contact finger 220 which is preferably in the form of a comb so as to be common to all the independent contact fingers 218. The other side of the A. C. supply is connected to the current coil 221 and the potential coil 222 of the (induction) motor 210. The opposite side of the current coil 221 is connected to the metal segment 208 on the disc 207.

The contact fingers 223 are connected to the opposite side of the potential coil 222, and the above connections are sufficient to cause the motor to run in one direction for example, clockwise, if the selected contact 212 happens to be on the metal segment 208. To enable the motor to run in the opposite direction when the circuit is not complete through 208 and 212 a suitable condenser 224 is inserted between the current coil 221 and the A. C. supply so as to change the phase between the coils 221 and 222. This is achieved by using another group of contact fingers 225 adapted to permit current to flow through the condenser 224 when the press button 230 is fully depressed by hand, so that 225 touches the contacts 220A which are connected to the A. C. supply and which will cause the motor 210 to rotate the disc 207 in a reverse (i. e. anti-clockwise) direction while the condenser 224 is not being shorted by contacts 208 and 212.

If the circuit were left as above, the motor would tend to hunt when the contact edge 215 reached the edge 216 of the metal plate, and to prevent this it is desirable to attach a friction disc device 226 on the motor shaft so as to close a contact 227 when rotating in one direction for example in an anti-clockwise direction. The contact 227 closes a D. C. circuit which may be from a battery H. T. radio or a separate rectifier to operate the magnet 228 to hold the contacts 225 and 220A together until the motor 210 stops or is reversed whereupon contact 227 opens. The contacts 218, 220 and 223 are held closed by the mechanical latch 229 in known manner, and will release the selector contact finger 218 when another button is pressed to select another station or to disconnect the control.

The above circuit arrangement functions similarly to that described with reference to Figure 1, as follows. When a station is to be selected and the chosen contact 212 happens to be in the insulated portion of the disc 207, the action of pressing the button 230 closes all the contact fingers 218, 220, 223, 225 and 220A, but as there is an open circuit between 208 and 212 current only flows between 220, 223 and coil 222 and between 220A, 225, condenser 224 and coil 221 whereby the motor rotates in an anti-clockwise direction and closes contact 227 to energise magnet 228 to keep 220A and 225 closed so that the motor continues to rotate the station selector disc 207 and tuning element in an anti-clockwise

direction until the contact edge 215 touches the plate edge 216. When this occurs A. C. current immediately flows through the lead 219 direct to the current coil 221, thus reversing the motor and opening contact 227 whereby contact fingers 220A and 225 are opened; at the same time the disc 207 is slightly reversed so that the edge 215 is again on the insulated portion 207 and no A. C. current can then reach the coil 221 through lead 219 or condenser 224 and therefore the motor stops, leaving the disc 207 and the tuning element in the desired tuned position.

Similar arrangements as have been described in connection with Figure 1 to provide rotation of the electric motor in an anti-clockwise direction when the selector member has been rotated to its extreme clockwise position and for breaking of the circuit by means of the insulating zone being shaped as at 56 and 57, Figure 2 may be provided in the modification described in connection with Figure 11 of the accompanying drawings by suitable shaping the insulating and conducting zones of the selector member 207.

The above circuit arrangements should mechanically tune a wireless receiver with sufficient accuracy for all frequencies below 1500 kc. (above 200 meters), but if higher frequencies are required or if easier adjustment is desired, it is advisable to make use of "automatic frequency control" in the radio circuit in addition to the above.

I claim:

1. In a tuning control for radio receiving apparatus provided with an adjustable tuning element, a selector member having a surface provided with conducting and insulating zones, a plurality of electrical contact members in sliding contact with the surface of the selector member, a reversible motor for driving both said tuning element and the selector member, a motor circuit for connecting the motor to a source of energizing current including said contact members and a plurality of operable relay devices for controlling the operation of said electric motor so as to adjust said selector member and said tuning element to predetermined positions, said motor circuit being arranged so that when the motor is energized through a selected one of the contact members which is in engagement with an insulating zone of said selector member, the electric motor is rotated in one direction and when a selected one of said contact members is

in engagement with a conducting zone of the selector member the electric motor is caused to rotate in the reverse direction.

2. In a tuning control arrangement for radio receiving apparatus as described in claim 1, a pair of voltage windings for said reversible electric motor, said voltage windings being arranged to control the direction of rotation of the motor, only one of said voltage windings being connected in the circuit during any one operation of the motor.

3. In a tuning control arrangement for radio receiving apparatus of the type described in claim 1, a pair of voltage windings for said electric motor to control the direction of rotation thereof, a source of energy for said motor, a condenser and means for applying energizing energy from said source to the motor through said condenser when the selected contact is in contact relation with an insulating zone of the selector member so as to cause the motor to rotate in a reverse direction to which it is caused to rotate when the selected contact is in contact with a conducting zone of the selector member.

25 4. In a tuning control arrangement for radio receiving apparatus as described in claim 1, a plurality of selectively operable means corresponding to said electrical contact members and adapted to select upon operation any one of said 30 contact members comprising push buttons any one of which is adapted to be depressed to select the corresponding contact member, latching means for holding the depressed one of said push buttons in a depressed position during operation 35 of the motor tuning means and means for automatically releasing said push button upon completion of the tuning operation.

5. In a tuning control arrangement as described in claim 1, change-over switching means 40 connected in said motor circuit and effective only when a desired predetermined position of the tuning element is approached from one direction, for causing the motor to move the tuning element beyond the desired position and reversing 45 the direction of rotation of the motor so as to move the tuning element back toward the desired position whereby the final rotation in adjusting the tuning element to a required position is always made in the same predetermined direction 50 irrespective of the initial direction of rotation of the tuning element.

FRANK ALLEN MITCHELL.
